POCKET LIGHTER

Hermann Zahn, Sulzbach (Main), Germany, assignor to Ibelo Metallwaren Gesellschaft mit beschraenkter
Haftung Hermann Zahn, Frankfurt am Main, Germany, a German firm

Application November 16, 1954, Serial No. 33,119

Term of patent 14 years

(Cl. D48—27)

Fig. 1 is a perspective view of a pocket lighter showing my new design;

Fig. 2 is a side elevational view thereof;

Fig. 3 is an elevational view looking at the left of Fig. 2; and

Fig. 4 is a top plan view.

The dominant features of my new design are shown in solid lines.

I claim:

The ornamental design for a pocket lighter, as shown and described.
